ABSTRACT

A control circuit for a lifting magnet which rapidly and automatically removes the residual magnetism in the magnet when the lifting current is released so that the magnet may be quickly unloaded. Provision is also provided for a fan control wherein the residual magnetism is not removed.

3 Claims, 1 Drawing Figure

PATENTED JAN 7 1975

CONTROL CIRCUIT FOR A LIFTING MAGNET

BACKGROUND OF THE INVENTION

1. Field of the Invention

This invention relates in general to controllers for electromagnets and in particular to an automatic circuit for rapidly removing the residual magnetism of a magnet.

2. Description of the Prior Art

Control circuits for magnets have provided for applying current of reverse polarity so as to demagnetize the magnet. However, such circuits have switched the current to the magnet at excessively high voltages thus resulting in short life of the switch contacts due to arcing. Other control circuits for magnets have been so slow that the magnet cannot be utilized as rapidly as possible.

SUMMARY OF THE INVENTION

The present invention provides an automatic control circuit for an electromagnet wherein the lifting current is applied in response to closing of a lift switch, and the load is dropped by depressing a drop switch which automatically and rapidly provides for demagnetizing the magnet which partially dissipates the magnetic residual voltage in a parallel resistor which further includes a relay which is actuated by the reverse voltage thus causing contacts to close to apply reverse polarity current to the magnet. A fan circuit is also provided which prevents the application of reverse polarity voltage to the magnet when a load is dropped.

Other objects, features and advantages of the invention will be readily apparent from the following description of certain preferred embodiments thereof, taken in conjunction with the accompanying drawing, although variations and modifications may be effected without departing from the spirit and scope of the novel concepts of the disclosure, and in which:

BRIEF DESCRIPTION OF THE DRAWING

The FIGURE is a schematic view of the invention.

DESCRIPTION OF THE PREFERRED EMBODIMENTS

Terminals L1, L2, and L3 are connected to a three phase AC power source and supply power through the switch contacts 51, 52, and 53 to the primary 10 of the delta connected windings 11, 12, and 13. Secondary 14 has connected windings 16, 17, and 18 and is connected to a rectifier 20 so as to provide DC voltage between leads 21 and 22. The rectifier 20 includes diodes D1, D2, D3, D4, D5, and D6 with diodes D1 and D2 connected in series and with a resistor R1 and capacitor C4 connected in series and the combination in parallel with the diodes D1 and D2. The end of winding 18 is connected to the junction point between diodes D1 and D2. Diodes D3 and D4 are connected in series and the combination in parallel with diodes D1 and D2 and the junction point between diodes D3 and D4 is connected to the end of winding 17. Diodes D5 and D6 are connected in series and the combination in parallel with diodes D3 and D4 and the junction point between the diodes D5 and D6 is connected to the end of winding 16. A diode D7 is connected from the diodes D1, D3, and D5 to fuse 25 which has its other side connected to lead 21. A fuse 30 is connected between lead

22 and the diodes D2, D4, and D6. A resistor R2 is connected from fuse 25 to fuse 30. A diode D8 is connected between leads 21 and 22 and poled as shown. Diode D8 is a selenium rectifier type with zener characteristics as for example the type sold under the trade marks Transorb, SURGE SUPPRESSOR or Volt Trap.

Lead 21 is the positive supply bus and lead 22 is the negative supply bus.

In the following description, the switch contacts controlled by the various relay will be initially described and are shown in the FIGURE before the magnet has been energized. Normally opened switch contacts 31a is connected in series with a resistor R3 and normally opened relay contacts 33b between leads 21 and 22. 15 Normally opened contacts 33a are connected in series with resistor R7 and normally opened switch contacts 31b between leads 21 and 22. An indicator light 36 is connected between leads 21 and 22 and indicates when power is supplied to the leads 21 and 22. Normally 20 closed contacts 32b are connected in series with normally opened contacts 34a and relay 33 and normally closed contacts 31c between leads 21 and 22. Normally opened switch contacts 32a are connected in series with normally closed drop switch 24 and normally closed fan switch 26 which is in series with relay 31 which is in series with normally closed switch contacts 33c between leads 21 and 22. A lift indicator light 39 is connected across the relay 31 and switch contacts 33c. Relay 32 is connected between the junction between relay 31 and switch contacts 33c and the junction point between switches 24 and 26.

The electromagnet 38 has its winding connected between the junction points of contacts 31a and resistor R3 and the junction point between resistor R7 and contacts 31b. A resistor R4 and a selenium rectifier with zener characteristics are connected in parallel with the winding of magnet 38. A relay 34 is connected from the junction point between resistor R4 and diode D9 and a pair of variable resistors R5 and R6 which are connected in series with their opposite side connected to a junction between contacts 31b and resistor R7. Relay 31 controls contacts 31a, 31b, and 31c. Relay 32 controls contacts 32a and 32b. Relay 33 controls contacts 33a, 33b, and 33c. Relay 34 controls contact 34a.

In operation, switch 23 is closed to energize relays 31 and 32. Relay 31 closes contacts 31a and 31b which applies positive power through contact 31a to the magnet 38 and the negative side of the power supply is connected to the magnet through contact 31b. The relay 31 also opens contact 31c. At the same time, relay 32 closes contact 32a which is in parallel with the lift switch 23 so as to hold power to the relays 31 and 32. Relay 32 also opens contact 32b which prevents relay 33 from being energized when relay 32 is energized. Power is applied to the magnet 38 which is then operated with full applied power so as to lift material in a normal manner.

When the load is to be dropped, switch 24 is opened by its push button which deenergizes relays 31 and 32. When relay 31 is deenergized, contacts 31a and 31b open to disconnect power from leads 21 and 22 to the magnet and contact 31c is closed. When relay 32 is deenergized, contact 32a is opened and contact 32b is closed.

When the contacts 31a and 31b are open, the applied power is removed from the magnet 38 which causes the

magnetic voltage to reverse and the voltage developed across the magnet 38 will dissipate through resistor R4 and diode D9. The voltage developed across the resistor R4 due to this current, energizes relay 34 which closes contact 34a to energize drop relay 33. Drop relay 33 closes contacts 33a and 33b which applies the DC voltage from leads 21 and 22 in the reverse polarity. Initially when relay 33 is energized since there are about 600 volts developed across the magnet, no current will flow from the power terminals since the power terminal voltage may be about 230 volts until the potential across the magnet decreases below 230 volts. When the voltage across the magnet 38 drops to below 230 volts, current will flow through contacts 33a, resistor R7, the magnet 38, resistor R3, and contacts 33b. It is to be noted that this current is in the direction opposite that used to initially energize the magnet.

Since the resistor R4 is in parallel with the magnet 38, the relay 34 will remain energized until the voltage across the magnet 38 has dropped to a relatively low value and in a operating magnet the relay R4 has been set by adjustment of the variable resistors R5 and R6 to drop out at about 46 volts. At that time, relay 34 de-energizes which opens up contact 34a. This deenergizes relay 33 which opens up contacts 33a and 33b and closes contact 33c. At this time, the circuit has returned to its initial condition before the lift switch 23 was closed and the residual magnetism in the magnet 38 has been reduced substantially to zero. The resistors R4, R5, and R6 are adjusted so that with an applied voltage of 230 volts from the power supply, the voltage would be dropped to about 30 volts across relay 34.

As soon as relay 33 is deenergized, the current from the magnet 38 will be dissipated through resistor R4 and diode D9. The characteristic of the diode D9 is the same as diode D8 and current goes in the reverse direction through the diode D9 and resistor R4, and the diode D9 limits the voltage across the magnet to a safe voltage of about 400 volts.

The fan circuit is controlled by switch 26 and is used when it is desired to remove the magnet from the power supply without reversing the current to it. When this operation is desired, the magnet will have been energized by closing switch 23 so as to apply current to the magnet through contacts 31a and 31b as described previously. When the fan switch 26 is depressed to open switch 26, the lift relay 31 will be deenergized thus opening contacts 31a and 31b and closing contacts 31c. This removes the power supply from the magnet 38 and it starts discharging through resistor R4 and diode D9 and the relay 34 is energized. However, since relay 32 is still energized and the contact 32b is open, the drop relay 33 will not be energized and reverse polarity of the power supply will not be applied to the magnet 38.

When the fan button switch 26 is released and closes, the relay 31 will immediately be energized and will apply energizing current to the magnet 38 through contacts 31a and 31b.

In a practical embodiment, a control circuit of this invention has been constructed as a fully contained integrated system and comprises a substantial improvement over the prior art magnetic control systems.

The resistor R4 may be a non linear resistor which increases its resistance as the voltage applied to it decreases.

Although this system has been described with respect to preferred embodiments, it is not to be so limited so

changes and modifications may be made therein which are within the full intended scope as defined by the appended claims.

We claim as our invention:

- 5 1. A control circuit for an electromagnet comprising, a direct current power supply with first and second terminals, a first switch connected between the one terminal of said power supply and one side of said electromagnet, a second switch connected between the second terminal of said power supply and the other side of the electromagnet, a first relay controlling said first and second switches, a third switch connected in circuit with said first relay and said power supply to energize it, a first resistor, a unilateral current device connected in series with said first resistor and the electromagnet in parallel with said first resistor and unilateral current device, a second relay having an energizing coil, a second resistor connected in series with energizing coil of said second relay and said first resistor in parallel with the energizing coil of said second relay and said second resistor, a third relay, a fourth switch controlled by said second relay and connected to said third relay and the combination connected across said power supply, a fifth switch controlled by said third relay and connected between said one terminal of said power supply and said other side of said electromagnet, a sixth switch controlled by said third relay and connected between said second terminal of said power supply and said one terminal of said electromagnet, a third resistor connected between said fifth switch and said other side of said electromagnet, said unilateral current device is a selenium rectifier with zener characteristics, and a fourth relay with one terminal connected to one terminal of the first relay, and a seventh switch connected between the other terminal of said fourth relay and the other terminal of said first relay, an eighth switch controlled by said fourth relay and connected in circuit with said third relay.
- 10 2. A control circuit according to claim 1 including a ninth switch controlled by fourth relay and connected in parallel with said third switch, a tenth switch with one terminal connected to the ninth switch and the other terminal connected to the seventh switch.
- 15 3. A control circuit for an electromagnet comprising, a direct current power supply with first and second terminals, a first switch connected between the one terminal of said power supply and one side of said electromagnet, a second switch connected between the second terminal of said power supply and the other side of the electromagnet, a first relay controlling said first and second switches, a third switch connected in circuit with said first relay and said power supply to energize it, a first resistor, a unilateral current device connected in series with said first resistor and the electromagnet in parallel with said first resistor and unilateral current device, a second relay having an energizing coil, a second resistor connected in series with energizing coil of said second relay and said first resistor in parallel with the energizing coil of said second relay and said second resistor, a third relay, a fourth switch controlled by said second relay and connected to said third relay and the combination connected across said power supply, a fifth switch controlled by said third relay and connected between said one terminal of said power supply and said other side of said electromagnet, a sixth switch controlled by said third relay and connected between said second terminal of said power supply and said one terminal of said electromagnet, a third resistor connected between said fifth switch and said other side of said electromagnet, said unilateral current device is a selenium rectifier with zener characteristics, and a fourth relay with one terminal connected to one terminal of the first relay, and a seventh switch connected between the other terminal of said fourth relay and the other terminal of said first relay, an eighth switch controlled by said fourth relay and connected in circuit with said third relay.
- 20 4. A control circuit according to claim 3 including a ninth switch controlled by fourth relay and connected in parallel with said third switch, a tenth switch with one terminal connected to the ninth switch and the other terminal connected to the seventh switch.
- 25 5. A control circuit for an electromagnet comprising, a direct current power supply with first and second terminals, a first switch connected between the one terminal of said power supply and one side of said electromagnet, a second switch connected between the second terminal of said power supply and the other side of the electromagnet, a first relay controlling said first and second switches, a third switch connected in circuit with said first relay and said power supply to energize it, a first resistor, a unilateral current device connected in series with said first resistor and the electromagnet in parallel with said first resistor and unilateral current device, a second relay having an energizing coil, a second resistor connected in series with energizing coil of said second relay and said first resistor in parallel with the energizing coil of said second relay and said second resistor, a third relay, a fourth switch controlled by said second relay and connected to said third relay and the combination connected across said power supply, a fifth switch controlled by said third relay and connected between said one terminal of said power supply and said other side of said electromagnet, a sixth switch controlled by said third relay and connected between said second terminal of said power supply and said one terminal of said electromagnet, a third resistor connected between said fifth switch and said other side of said electromagnet, said unilateral current device is a selenium rectifier with zener characteristics, and a fourth relay with one terminal connected to one terminal of the first relay, and a seventh switch connected between the other terminal of said fourth relay and the other terminal of said first relay, an eighth switch controlled by said fourth relay and connected in circuit with said third relay.
- 30 6. A control circuit according to claim 5 including a ninth switch controlled by fourth relay and connected in parallel with said third switch, a tenth switch with one terminal connected to the ninth switch and the other terminal connected to the seventh switch.
- 35 7. A control circuit for an electromagnet comprising, a direct current power supply with first and second terminals, a first switch connected between the one terminal of said power supply and one side of said electromagnet, a second switch connected between the second terminal of said power supply and the other side of the electromagnet, a first relay controlling said first and second switches, a third switch connected in circuit with said first relay and said power supply to energize it, a first resistor, a unilateral current device connected in series with said first resistor and the electromagnet in parallel with said first resistor and unilateral current device, a second relay having an energizing coil, a second resistor connected in series with energizing coil of said second relay and said first resistor in parallel with the energizing coil of said second relay and said second resistor, a third relay, a fourth switch controlled by said second relay and connected to said third relay and the combination connected across said power supply, a fifth switch controlled by said third relay and connected between said one terminal of said power supply and said other side of said electromagnet, a sixth switch controlled by said third relay and connected between said second terminal of said power supply and said one terminal of said electromagnet, a third resistor connected between said fifth switch and said other side of said electromagnet, said unilateral current device is a selenium rectifier with zener characteristics, and a fourth relay with one terminal connected to one terminal of the first relay, and a seventh switch connected between the other terminal of said fourth relay and the other terminal of said first relay, an eighth switch controlled by said fourth relay and connected in circuit with said third relay.
- 40 8. A control circuit according to claim 7 including a ninth switch controlled by fourth relay and connected in parallel with said third switch, a tenth switch with one terminal connected to the ninth switch and the other terminal connected to the seventh switch.
- 45 9. A control circuit for an electromagnet comprising, a direct current power supply with first and second terminals, a first switch connected between the one terminal of said power supply and one side of said electromagnet, a second switch connected between the second terminal of said power supply and the other side of the electromagnet, a first relay controlling said first and second switches, a third switch connected in circuit with said first relay and said power supply to energize it, a first resistor, a unilateral current device connected in series with said first resistor and the electromagnet in parallel with said first resistor and unilateral current device, a second relay having an energizing coil, a second resistor connected in series with energizing coil of said second relay and said first resistor in parallel with the energizing coil of said second relay and said second resistor, a third relay, a fourth switch controlled by said second relay and connected to said third relay and the combination connected across said power supply, a fifth switch controlled by said third relay and connected between said one terminal of said power supply and said other side of said electromagnet, a sixth switch controlled by said third relay and connected between said second terminal of said power supply and said one terminal of said electromagnet, a third resistor connected between said fifth switch and said other side of said electromagnet, said unilateral current device is a selenium rectifier with zener characteristics, and a fourth relay with one terminal connected to one terminal of the first relay, and a seventh switch connected between the other terminal of said fourth relay and the other terminal of said first relay, an eighth switch controlled by said fourth relay and connected in circuit with said third relay.
- 50 10. A control circuit according to claim 9 including a ninth switch controlled by fourth relay and connected in parallel with said third switch, a tenth switch with one terminal connected to the ninth switch and the other terminal connected to the seventh switch.
- 55 11. A control circuit for an electromagnet comprising, a direct current power supply with first and second terminals, a first switch connected between the one terminal of said power supply and one side of said electromagnet, a second switch connected between the second terminal of said power supply and the other side of the electromagnet, a first relay controlling said first and second switches, a third switch connected in circuit with said first relay and said power supply to energize it, a first resistor, a unilateral current device connected in series with said first resistor and the electromagnet in parallel with said first resistor and unilateral current device, a second relay having an energizing coil, a second resistor connected in series with energizing coil of said second relay and said first resistor in parallel with the energizing coil of said second relay and said second resistor, a third relay, a fourth switch controlled by said second relay and connected to said third relay and the combination connected across said power supply, a fifth switch controlled by said third relay and connected between said one terminal of said power supply and said other side of said electromagnet, a sixth switch controlled by said third relay and connected between said second terminal of said power supply and said one terminal of said electromagnet, a third resistor connected between said fifth switch and said other side of said electromagnet, said unilateral current device is a selenium rectifier with zener characteristics, and a fourth relay with one terminal connected to one terminal of the first relay, and a seventh switch connected between the other terminal of said fourth relay and the other terminal of said first relay, an eighth switch controlled by said fourth relay and connected in circuit with said third relay.
- 60 12. A control circuit according to claim 11 including a ninth switch controlled by fourth relay and connected in parallel with said third switch, a tenth switch with one terminal connected to the ninth switch and the other terminal connected to the seventh switch.
- 65 13. A control circuit for an electromagnet comprising, a direct current power supply with first and second terminals, a first switch connected between the one terminal of said power supply and one side of said electromagnet, a second switch connected between the second terminal of said power supply and the other side of the electromagnet, a first relay controlling said first and second switches, a third switch connected in circuit with said first relay and said power supply to energize it, a first resistor, a unilateral current device connected in series with said first resistor and the electromagnet in parallel with said first resistor and unilateral current device, a second relay having an energizing coil, a second resistor connected in series with energizing coil of said second relay and said first resistor in parallel with the energizing coil of said second relay and said second resistor, a third relay, a fourth switch controlled by said second relay and connected to said third relay and the combination connected across said power supply, a fifth switch controlled by said third relay and connected between said one terminal of said power supply and said other side of said electromagnet, a sixth switch controlled by said third relay and connected between said second terminal of said power supply and said one terminal of said electromagnet, a third resistor connected between said fifth switch and said other side of said electromagnet, said unilateral current device is a selenium rectifier with zener characteristics, and a fourth relay with one terminal connected to one terminal of the first relay, and a seventh switch connected between the other terminal of said fourth relay and the other terminal of said first relay, an eighth switch controlled by said fourth relay and connected in circuit with said third relay.

terminal of said electromagnet, a third resistor connected between said fifth switch and said other side of said electromagnet, said unilateral current device is a selenium rectifier with zener characteristics, a fourth resistor connected between said sixth switch and said one terminal of said power supply, said second resistor

is variable so as to set the deenergization point of said second relay, and said first resistor is non linear such that it increases its resistivity as the applied voltage decreases.
